UNITED STATES PATENT OFFICE

GEORGE CORWIN FRASER AND NORMAN PETO FRASER, OF CARSONVILLE,
MICHIGAN.

DAMPER.

SPECIFICATION forming part of Letters Patent No. 593,930, dated November 16, 1897.

Application filed December 5, 1896. Serial No. 614,526. (No model.)

To all whom it may concern:

Be it known that we, GEORGE CORWIN FRA-
SER and NORMAN PETO FRASER, both of Car-
sonville, in the county of Sanilac and State
5 of Michigan, have invented certain new and
useful Improvements in Dampers, of which
the following is a full, clear, and exact de-
scription.

Our invention relates to improvements in
10 stovepipe-dampers; and the object of our in-
vention is to produce a superior arrangement
of dampers of that class which may be ma-
nipulated so as to promote a rapid draft, and
may also be turned so as to make the prod-
15 ucts of combustion pursue a tortuous or zig-
zag course through the pipe, to the end that
the draft may be checked somewhat and all
the heat radiated and rendered effective.

A further object of our invention is to ar-
20 range these dampers in pairs in such a man-
ner that each pair may be independently op-
erated.

Our invention consists of certain features
25 of construction and combinations of parts,
which will be hereinafter described and
claimed.

Reference is to be had to the accompanying
drawings, forming a part of this specification,
in which similar figures of reference indicate
30 corresponding parts in all the views.

Figure 1 is a longitudinal section on the
line 1 1 in Fig. 2 of a stovepipe provided
35 with our improved dampers, the dampers be-
ing shown in cross-section. Fig. 2 is an out-
side elevation of the pipe and the damper ar-
rangement. Fig. 3 is a longitudinal section
40 on the line 3 3 of Fig. 1. Fig. 4 is a sectional
plan of one of the dampers. Fig. 5 is a sec-
tional elevation of one of the connecting-rods
45 and its operating-pinion, the rod being shown
depressed; and Fig. 6 is a similar view with
the rod raised.

The stovepipe 10 is of the usual kind, and
arranged at intervals within it are dampers
45 11, these being hung so as to swing to oppo-
site sides of the pipe alternately, as shown in
Fig. 1, and when thus tilted they cause the
products of combustion to pursue a sinuous
50 course through the pipe, as illustrated by the
arrows, so that the heat being checked is ra-
diated from the pipe. The dampers may,

however, be turned edgewise in the pipe, as
illustrated by dotted lines in Fig. 1, so that
there will be a straight draft through the
pipe.

Each damper 11 is of a generally semicir-
55 cular shape, so as to half-close the pipe when
it is in a nearly horizontal position, and on
opposite edges of the damper are keepers 12,
which are nearly rectangular in cross-sec- 60
tion and which are adapted to engage the
squared sections 13 of the damper-stem 14,
which projects through the funnel, being held
to turn therein, and the stem is provided near
the center with notches 16, which are adapted 65
to engage a tooth 17 on the damper, and as
it is necessary to spring the stem slightly
to have it engage the tooth the tooth and
notches serve to hold it in place when once
it is engaged.

The dampers are connected in pairs, and
one stem of each pair is provided with a suit-
able handle 15, while both are provided out-
side the pipe with mutilated pinions 18, which
are adapted to engage racks 19 in the loops 75
20 of the connecting-rods 21, which connect
the adjacent pairs of stems, and the racks
and pinions are arranged in such a way that
when one stem is turned it will throw its dam-
per in one direction and move the connect- 80
ing-rod so as to turn the next adjacent dam-
per in the opposite direction, or by turning
the damper straight in the funnel the next
damper will be similarly turned, as illustrated
in Fig. 2.

Each loop 20 has a leaf-spring 22 held in
one side and pressing against the correspond-
ing pinion 18. Each pinion 18 has a plane
surface 23, which turns against its correspond-
ing spring 22 when the dampers are moved 90
to a perpendicular position. By these means
the dampers are held raised except when pur-
posely lowered.

It will be observed that the connecting-rods
and pinions are outside of the stovepipe, so 95
that they are not liable to be excessively heat-
ed and warped. Each pair of dampers may
be independently worked, so that, if desired,
one set of dampers may be turned straight
in the funnel and another set turned into a 100
nearly horizontal position, as shown by dot-
ted lines in Fig. 2, and it will of course be

understood that the pipe may be provided with any desired number of these dampers.

Having thus described our invention, we claim as new and desire to secure by Letters 5 Patent—

1. The combination with a flue, of two dampers mounted to turn therein and each having an area less than the width of the flue, a pinion connected with each damper, and a 10 rack-bar extending between and connected with the pinions, the rack-bar engaging opposite sides of the pinions to turn the dampers oppositely, substantially as described.

2. The combination with a flue, of two dampers mounted to turn therein on axes transverse to the flue and each having an area less than the width of the flue, a pinion fixed to the trunnion of each damper, and a bar having a loop at each end, the loops respectively 15 inclosing the pinions and each loop having rack-teeth at one of its sides whereby to be connected with the pinions and the rack-teeth 20

being oppositely located with reference to each other, substantially as described.

3. The combination with a flue, of two dampers mounted to turn therein on axes transverse to the flue and each having an area less than the width of the flue, a pinion fixed to the trunnion of each damper, a bar extending between the pinions and having a loop at 25 each end, the loops respectively inclosing the pinions, and one side of each loop having rack-teeth to respectively engage the pinions, the rack-teeth being oppositely located with reference to each other, and a spring held 30 within each loop of the bar and respectively pressing the pinions into engagement with the rack-teeth, substantially as described.

GEORGE CORWIN FRASER.
NORMAN PETO FRASER.
